Int. Cl. D25—04

U.S. Cl. D13—1

FIG. 1 is a top plan view of a building unit having a hexagonally shaped space element supported by a pair of parallelogram shaped support columns.

FIG. 2 is a left side elevation view of the building unit of FIG. 1.

FIG. 3 is a front elevation view of the building unit of FIG. 1.

FIG. 4 is a right side elevation view of the building unit of FIG. 1.

FIG. 5 is a rear elevation view of the building unit of FIG. 1.

FIGS. 6-15 are top plan views of a building unit similar to FIG. 1 wherein the parallelogram shaped support columns are arranged at various positions with respect to the hexagonally shaped space element. The views similar to FIGS. 2-5 for the units of FIGS. 6-15 will be readily apparent to those skilled in the art.

This application is a continuation-in-part of my application Ser. No. D. 14,261, filed Nov. 1, 1968.

I claim:

The ornamental design for a building unit substantially as shown and described.
